UNITED STATES PATENT OFFICE.

FERDINAND W. NITARDY, OF BROOKLYN, NEW YORK, AND RUTHERFORD BOYD, OF LEONIA, NEW JERSEY, ASSIGNEES TO E. R. SQUIBB & SONS, OF NEW YORK, N. Y., A CORPORATION OF NEW YORK.

DESIGN FOR A COVER FOR A COLD-CREAM JAR OR LIKE CONTAINER.

Application filed January 14, 1926. Serial No. 16,066. Term of patent 14 years.

To all whom it may concern:

Be it known that we, FERDINAND W. NITARDY, residing at and whose post-office address is 29 Monroe Place, Brooklyn, county of Kings, and State of New York, and RUTHERFORD BOYD, residing at and whose post-office address is 112 Prospect Place, Leonia, county of Bergen, and State of New Jersey, citizens of the United States, have invented a new, original, and ornamental Design for a Cover for a Cold-Cream Jar or like Container, of which the following

is a specification, reference being had to the accompanying drawing, forming part thereof.

Figure 1 is a top view; and

Figure 2 is a side view of a cover for a cold cream jar or like container embodying our new design.

We claim:

The ornamental design for a cover for a cold cream jar or like container, as shown.

FERDINAND W. NITARDY.
RUTHERFORD BOYD.
